FIG. 5

Inventor.

Oral A. King.

UNITED STATES PATENT OFFICE.

ORAL A. KING, OF SOUTH NORFOLK, VIRGINIA.

TOOTHBRAH CASE.

Application filed February 7, 1927. Serial No. 166,446.

This invention relates to improvements in toilet cases particularly adapted for use in connection with tooth brushes, the present invention being an improvement on the dis-
5 closure in my Patent No. 1,604,918 dated October 26, 1926.

The main object of the present improvement is to provide a device that may be readily carried in the pocket of the user and having included as a part thereof novel means for holding the tooth brush in a tubular enclosure when not in use with material advantages from a sanitary standpoint, and also to include a structure which provides for holding a tube of tooth paste within the enclosure with the brush, and further to facilitate projection of the brush for use without separation from any part of the holder, and at the same time render the tooth paste readily accessible.

A further object of the invention is to simplify the construction and arrangement of the parts of the enclosing means for the tooth brush of the character specified where-
25 in the main enclosing element or body is ma- terially reduced in its structural features and wherein the brush carrying head serves as the end closure for the body of the device when the tooth brush together with the tube
30 of paste are retracted within the said body.

A still further object of the invention is to provide for ventilation and drying of the brush after use when enclosed in the main body of the holder to shield the brush, and also to generally improve the structure whereby it is made more efficient in its service.

With the foregoing and other objects and advantages the invention consists in the construction and arrangement of the several parts which will be more fully hereinafter de-
40 scribed and claimed.

In the drawing:—

Fig. 1 is a perspective view of a tooth brush organization embodying the features of the invention and showing the brush projected for use.

Fig. 2 is a longitudinal vertical section of the improved tooth brush organization showing the brush and tube of paste enclosed and fully sealed within the main body or tubular casing with a tubular cover fitted to the latter.

Fig. 3 is a longitudinal vertical section through the improved tooth brush organization as shown and arranged in Fig. 1.

Fig. 4 is a transverse vertical section on the line 4, 4, Fig. 2.

Fig. 5 is a transverse vertical section on the line 5, 5, Fig. 3.

The improved tooth brush case consists of 60 a main tubular casing or body 5 with both ends 6 and 7 normally open, the end 7 being formed with screw-threads 8 by corrugating or otherwise constructing the same and con-
tracting the terminal or the outmost corrugation, as at 9, by slightly crimping the latter, to form a stop means. Telescopically mounted in and cooperating with the main tubular enclosure or body 5 is a tubular cover 10 which is readily removable and is adapted 70 to be normally applied over the screw-thread extremity 7 of the enclosure or body 5 when the improved device is arranged in compact form for carrying the same in the pocket of the user, as shown by Fig. 2. When the brush is projected the cover 9 may be applied tem-
porarily to the opposite end of the main en-
closure or body 5, as clearly shown by Figure
1. The cover 10 is fully open at one end and
closed at the opposite end, as at 11, and has
a ventilating opening 11^a formed in the center
of the closed end, the latter being pref-
erably formed concavo-convex in contour.
The screw-threads 8 in the present instance
are formed directly in the material of the 80
enclosure or body 5, a feature which is
materially distinguished from the structure
disclosed in my patent aforesaid. These
screw-threads 8 extend only a comparatively
short distance over the length of the main 85
enclosure or body 5, or only a sufficient dis-
tance to provide a positive holding means for
a part which cooperates with the said en-
closure or body.

The improved tooth brush organization 95
also includes a brush carrying head 12 which
is hollow and has a rear concavo-convex clos-
ing wall 13, and a front flat wall 14 with an
eccentrically located opening 15 together with
a socket 16 projected therefrom above the 100
said opening. The socket 16 is, therefore, ec-
centrically projected from the head 12, and
the greater length thereof extends in advance
of said head and the remaining part projects
into the head so as to straighten the mount-
ing of this socket. In contour the socket is
slightly flattened and resilient, a slot 16^a being
formed longitudinally thereof to permit
it to sufficiently yield to receive the handle
17 of a tooth brush 18, the handle 17 in this 105
110

instance being shorter than the handles of tooth brushes as ordinarily constructed. The handle 17 is inserted in and frictionally held by the socket 16, the latter yielding or expanding when the handle 17 is inserted therein thereby increasing the gripping action of the socket on the handle. The tooth brush handle 17 and brush 18 remain intact with the head 12 under ordinary usage of the improved device, but the handle 17 may be withdrawn from the socket with the brush 18 and replaced by another similar brush and handle in the event that the brush becomes worn and unfit for further service. The outer side of the head 12 is screw-threaded, as at 19, to engage the threads 8 of the main enclosure of body 5, the head 12 when fully projected within the main enclosure or body being held against outward separation beyond a predetermined extent by the outer terminal stop or crimp 9 of the threads 8. The head 12, when fully moved in an outward direction, has the flat side 14 in alinement with the outer terminal of the main enclosure or body 5. In the rear concavo-convex closing end 13 of the head 12 vertically alined openings 20 are formed to loosely receive a ring 21, the material between the openings 20 being outstruck, as at 22, as a reinforcing support for the ring 21. This ring 21 is adapted to serve as a means of attaching the improved device as a whole to a suspending or other means as desired, and the openings 20 serve as ventilating apertures to permit the air to circulate through the head and through the latter by way of the openings 15 to the brush 18 and handle 17. The main enclosure or body 5 also has a series of ventilating openings 23 formed therein to permit the air to enter the said enclosure or body for ventilating and drying purposes and to maintain the brush in good hygienic condition.

The opening 15 is particularly intended to loosely receive the reduced or neck extremity 24 of a tube 25 of the usual form adapted to hold tooth paste or other tooth cleansing material. When the tooth brush and head 12 are retracted or telescoped within the main enclosure or body 5, the tube 25 is disposed, as shown by Fig. 2, with the neck 24 thereof inserted through the opening 15 and the body of the tube lying along and close to the handle 17.

When the parts of the tooth brush case are reduced to compact form, the head 12 is detached, or the threads 19 thereof are separat-

ed from the threads 8 of the main enclosure or body 5 by subjecting the said brush, handle and head to rotary movement, and may then be pushed rearwardly or telescoped within the enclosure or body 5 with the brush until the concavo-convex end 13 reaches the rear of the rear open end 6 of the enclosure or body 5, or until it is stopped by a slight contraction of the metal around the rear open end of the enclosure or body, as at 26, it being understood that the tube 25 carrying the paste or other tooth cleansing material will be first arranged, as shown by Figure 2. The cover 10 is then applied over the front end of the enclosure or body 5, as also shown by Fig. 2, and in this condition the brush 18 and its handle 17 together with the tube 25 will be fully enclosed and protected. When it is desired to use the brush 18, the latter is pulled outwardly, thus drawing the head 12 therewith, and associating the threads 8 and 19 by rotating the head within the enclosure or body, or vice versa, the tube 25 being first removed.

This improved tooth brush holding means is very simple in its operation and will serve as an effective means for preventing corrosion from dampness of the brush or the bristles of the latter, owing to the ventilating openings provided in the several parts which permit a thorough circulation of air throughout the length of the interior of the improved device.

While the invention as heretofore described is believed to be a practical and preferred embodiment of the invention, yet it is to be understood that such changes and alterations in the construction and arrangement of the several parts, as the exigencies of use may show to be necessary or desirable, may be made without transcending the scope of the invention as defined by the appended claim.

What is claimed as new is:—

The combination with an open-ended cylindrical enclosure for a tooth-brush, of an insertable, hollow plug therefor, one face of said plug being centrally raised and apertured, a ring mounted in said apertures and projecting from said plug, and a brush-secur ing split tubular socket bodily carried by the cap and projecting in an opposite direction to the ring, said tube being disposed eccentrically of the plug.

In testimony whereof I have hereunto set my hand.

ORAL A. KING.
